UNITED STATES PATENT OFFICE.

JOHN C. ROGERS, OF HOUSTON, TEXAS, ASSIGNOR TO HOUSTON BLOW PIPE AND SHEET METAL WORKS, OF HOUSTON, TEXAS, A CORPORATION.

CONDENSER DRUM.

Application filed August 24, 1925. Serial No. 52,206.

To all whom it may concern:

Be it known that I, JOHN C. ROGERS, a citizen of the United States, residing at Houston, in the county of Harris and State 5 of Texas, have invented certain new and useful Improvements in a Condenser Drum, of which the following is a specification.

This invention relates to new and useful improvements in a condenser drum.

One object of the invention is to provide 10 a drum of the character described embodying a foraminated covering mounted on a frame of such formation as not to obstruct, or restrict the free inflow of air through the

covering.

Another object of the invention is to provide 15 a condenser drum embodying a frame and a foraminated covering thereon, said frame being of such construction that it will not collect foreign matter to clog the cover 20 openings or restrict the inflow of air there-through.

A further feature of the invention resides 25 in the provision of a drum which is strong and durable and yet of light and simple construction so that it may be cheaply and easily produced.

With the above and other objects in view 30 this invention has particular relation to certain novel features of construction, operation and arrangement of parts an example of which is given in this specification and illustrated in the accompanying drawings, wherein:—

Figure 1 shows a fragmentary longitudinal sectional view of the drum.

Figure 2 shows a fragmentary cross sectional view.

Figure 3 shows a side elevation of the 40 drum, partly in section, and shown as mounted in a condenser, and

Figure 4 shows an enlarged fragmentary side view of one of the framework ribs, showing the foraminated covering, as mounted 45 thereon.

Referring now more particularly to the drawings, wherein like numerals of reference 50 designate similar parts in each of the figures the numeral 1 designates the casing forming part of a cotton condenser into which the lint flue 2 leads. The numeral 3 designates the condenser drum as a whole which

is rotatably mounted in this casing, and leading out from the respective ends of the drum are the suction flues 4, 4.

The drum is rotated, in any conventional manner, and the lint cotton is delivered onto the drum and deposited thereon in a bat, and the dirt and foreign matter passes on through the drum and out through the flues 60 4, 4. The bat, as formed, is discharged from the drum in the conventional manner common to condensers of this character. The novel feature on this invention resides in the drum construction, which will now 65 be described.

The drum consists of a frame and a foraminated covering thereon. The frame includes the annular end supports 5, 5 whose inner sides are reduced forming the annular 70 supporting shoulders 6, 6. Lengthwise supporting ribs 7, are provided whose ends rest on the shoulders 6. These ribs have spaced projections 8, on their outer edges, the projections of the ribs being disposed in spiralled relation and their outer ends being provided with notches 9 to receive the spiralled wire 10 which is seated therein. A foraminated covering 11 is supported on the

framework thus formed, and is secured 75 thereon by the surrounding end bands 12, 12 which also secure the ribs 7 in place. It will be noted that the ribs 7 are disposed radially and edgewise with respect to the covering 11, and are relatively thin so that they will 80 not readily collect foreign matter to clog, or restrict the screening surface of said covering. The covering is also held spaced from the outer edges of the ribs, by means of the projections 8 and the wire 10 so that the

ribs themselves will not obstruct, or restrict the free inflow of air, to the end that the lint cotton will be deposited in an even bat on the drum. The spaces 13, between the 85 projections 8, provide ample air passageways between the covering and ribs, so as to prevent the collection of clogging material on the ribs and to form no obstruction to the covering thus insuring the free and uniform passage of air therethrough so that an even bat will be formed thereon.

What I claim is:

1. A drum including a framework comprising spaced ribs having radiating pro-

jections and a cover support carried by said projections, and a foraminated cover around and supported by said support.

2. A drum including annular end supports, ribs spaced apart and whose ends are anchored to the respective end supports, projections carried by the ribs and disposed in spiralled relation, a cover support disposed spirally and seated on said projections, and 10 a foraminated cover around said cover support.

3. A drum including end supports, radially disposed ribs whose ends are anchored to said supports, outward projections on said 15 ribs whose ends are provided with notches,

said projections being disposed spirally, a cover support disposed spirally and seated in said notches, and a foraminated cover around said cover support.

4. A drum including a framework comprising spaced ribs having radiating projections, said projections being spaced apart, a cover support carried by said projections, a foraminated cover around and supported by said support, the spaces between the projections being provided to prevent the obstructing of said foraminated cover. 20 25

In testimony whereof I have signed my name to this specification.

JOHN C. ROGERS.
